ARCHIE W. STEELE, OF BLOOMFIELD, NEW JERSEY, ASSIGNOR TO WILFORD J. HAWKINS, OF MONTCLAIR, NEW JERSEY.

ELECTRIC FUSE.

1,335,404.

Specification of Letters Patent. Patented Mar. 30, 1920.

Application filed May 24, 1919. Serial No. 299,519.

To all whom it may concern:

Be it known that I, ARCHIE W. STEELE, a subject of the King of Great Britain, residing at Bloomfield, in the county of Essex, 5 State of New Jersey, have invented certain new and useful Improvements in Electric Fuses; and I do hereby declare the following to be a full, clear, and exact description of the invention, such as will enable others 10 skilled in the art to which it appertains to make and use the same.

This invention relates to electric fuses and is directed to the provision of an improved construction for such fuses. The object of 15 the invention is to produce a novel form of fuse which is of simple construction, the parts of which may be manufactured at very low cost, which permits of renewing a burned-out fuse with great facility and in 20 which the end caps on the ends of the tube of insulating material are gripped tightly to the ends of the tube by expanding within them the portions of the tube which they inclose.

25 A fuse constructed in accordance with the invention consists of a tube of fiber or other insulating material the ends of which are provided with dove-tail slots; in each of these slots is a metallic plate, the sides of 30 which are preferably inclined to correspond to the side walls of the slots in the insulating tube. The distinguishing characteristic of the fuse is that by drawing together the plate and the end cap at each end of the 35 fuse, as by means of suitably arranged screws, the end of the fuse-wire is gripped between the plate and the end cap and at the same time the movement of the plate in its slot toward the end cap results in expansion of the portions of the insulating tube 40 on opposite sides of the slot in the end of the tube within the end cap so that they bind the end cap tightly upon the tube.

A construction constituting an embodiment 45 of the present invention is illustrated in the accompanying drawing. In this drawing, Figure 1 is a central longitudinal section of the fuse; Fig. 2 is a similar view, the plane of the section being at right angles 50 to the plane of Fig. 1; Fig. 3 is a transverse section on line 3—3 of Fig. 2; Fig. 4 is an elevation of the insulating tube, and Fig. 5 is a perspective view of the plate which fits 55 within the slot in the end of the tube.

Referring to these drawings, the tube of

insulating material which constitutes the casing of the fuse, is indicated at 6. In each of its ends is a dove-tail slot, the side walls of which converge toward the end of the tube. The preferred shape of this slot 60 is indicated clearly in Figs. 1 and 4. The ends of the portions of tube 6 lying on opposite sides of the slot appear in Fig. 3.

In the slot in each end of the tube 6 is a plate 7, preferably of the construction shown 65 in Fig. 5. The plate is rectangular, it is of less thickness than the depth of the dove-tail slot in which it lies, and the opposite sides of the plate are inclined as shown at 8, the inclination corresponding to the inclination 70 of the side walls of the dove-tail slots in the tube 6. In one end of the plate 7 is a slot 9, and the plate is provided with two threaded openings 10 on opposite sides of its center line. 75

The fuse-wire 11 extends through the tube 6 as shown; its ends pass through the slots 9 in the plates 7 at opposite ends of the fuse and are bent over so as to extend along the faces of the plate 7 as indicated in Figs. 2 80 and 3.

On each end of the tube 6 is an end-cap 12 provided with two openings on opposite sides of its center line positioned to correspond with the openings 10 in the plate 7. 85 The interior surface of the end portion of each of the end caps is adapted to bear against the end of the tube 6, that is, against the ends of the portions of tube 6 lying on opposite sides of the dove-tail slot. Screws 13 90 pass through the openings in the end cap 12 and enter the threaded openings 10 in the plate 7. As these screws are tightened up, the plate 7 is drawn outwardly toward the adjacent end cap and in doing so it grips the 95 end of the fuse-wire between the plate and the end cap so as to hold the fuse-wire firmly and at the same time make good electrical connection thereto; furthermore, as the plate 7 moves outwardly in response to 100 tightening of the screws 13, its inclined side walls act upon the inclined side walls of the portions of tube 6 on opposite sides of the slot to expand them. This expansion of these portions of the end of tube 6 carries 105 them into hard contact with the interior surface of the end cap 12 with the result that the end cap is gripped firmly to the tube 6. During this operation of tightening the screws 13, the end cap 12 is braced against 110

the end of tube 6 as the interior of the end cap bears against the end wall of tube 6 and the plate 7 is moved bodily toward the end of the end cap to effect the gripping of 5 the fuse-wire and the expansion of the end of tube 6 into gripping relation to the end cap.

Each of the end caps 12 may have a switch blade 14 secured thereto for coöperation 10 with the clips of a switch, though, of course, such blades 14 would be omitted if the fuse were of the type in which the switch clips coöperate directly with the walls of the end caps 12.

15 It will be noted that the construction is such that no special precaution is necessary in assembling the parts of the fuse to insure that the two blades 14 will lie in the same plane. These blades are secured rigidly to 20 the end caps and the end caps must be positioned accurately with reference to the axis of the fuse in order to bring the screw holes in the end caps into accurate registry with the screw holes in the plates 7; the plates 7 25 are, in turn, positioned accurately with respect to the axis of the fuse by the walls of the slots in the tube 6.

While I have illustrated and described the construction which I prefer to employ and 30 which I consider the best embodiment of my invention, I wish it understood that the invention may be employed in different constructions and I aim to cover such modified constructions by the terms of the appended 35 claims. The essentials of utilization of the invention are that the end-caps shall coöperate directly with the ends of the insulating tube 6 so as to be braced thereon; that the plates 7 shall be movable relatively to the 40 tube 6 toward and away from the ends of the end-caps; and that the coöperating surfaces of the side walls of the plates and the walls of the slots in the tube 6 shall be such that when the plates are so moved, they will 45 cause expansion of portions of the tube 6 with the result that the end-caps will be gripped interiorly and held securely. Such a construction permits of ready renewal of the fuse-wire when the fuse has been burned 50 out, the renewal requiring but a few moments and no tools other than a screw-driver. Furthermore, the construction is one which permits of manufacture at very 55 low cost as the number of parts employed is small and the operations incident to manufacturing and assembling are simple; it will be appreciated that a considerable number of tubes 6 may be slotted simultaneously after gripping them in position in alignment 60 on a suitable machine and also that the plates 7 may be cut from a metal strip after the latter has been suitably shaped.

The construction described above and 65 illustrated in the accompanying drawings is that which I prefer to employ, but I wish it

understood that the invention may be embodied in many other constructions. In the form in which the invention is embodied as above described, the movement of the plates bodily relatively to the length of the 70 insulating tube and toward the ends of the end-caps is utilized for two purposes, first, for the purpose of gripping the fuse-wire to make good electrical and mechanical connection to it, and second, for the purpose of 75 expanding the end portions of the tube to cause them to grip the inclosing end-caps. It is not essential that this bodily movement of the plates be employed for both of these purposes and when the fuse-wire is in the 80 form of a flat strip instead of a round wire, it is preferable to effect the mechanical and electrical connection to the ends of the fuse-wire in some way other than by resorting to the bodily movement of the plates relatively 85 to the tube. In that case, the movement of the plates is employed for the sole purpose of expanding the ends of the tube to grip the end-caps.

All such modifications of the construction 90 embodying the present invention I consider to be within the scope of the invention and I aim to cover them by the terms of the claims appended hereto.

I claim:

1. A fuse comprising the combination of a tube of insulating material having dove-tail slots in its ends, plates located in the slots in the tube, end caps upon the tube bearing directly against the ends of the tube, 100 a fuse-wire passing through the tube and having its ends lying between the plates and the end caps, and means for drawing the plates bodily toward the end caps to grip the ends of the fuse-wire between the plates and the end caps and to expand the ends of the tube into the end caps by the coöperation of the plates with the side walls of the dove-tail slots in the tube as the plates are moved 105 toward the end caps. 110

2. In a fuse, a tube of insulating material having a dove-tail slot across its end, a metallic plate located in the slot and of less thickness than the depth of the slot, said plate having its sides inclined to correspond to the side walls of the dove-tail slot and having a slot in one of its walls, a fuse-wire extending through the slot in the plate and having its end bent to extend along the plate, an end cap on the tube bearing directly against the end of the tube on opposite sides of the slot and two screws passing through the end of the end-cap and on opposite sides of the end of the fuse-wire and entering threaded holes in the said plate. 115 120

3. A fuse comprising the combination of a tube of insulating material having dove-tail slots in its ends, plates located in the slots in the tube, end-caps upon the tube bearing directly against the ends of the 125 130

tube, a fuse-wire within the tube, means for making electrical connection to the fuse-wire and means for drawing the plates bodily toward the end caps to expand the ends 5 of the tube into the end caps by the coöperation of the plates with the side walls of the dove-tail slots in the tube as the plates are moved toward the end caps.

4. In a fuse, a tube of insulating material having a dove-tail slot across its end, 10 a metallic plate located in the slot and of less thickness than the depth of the slot,

said plate having its sides inclined to correspond to the side walls of the dove-tail slot, an end-cap on the tube bearing directly 15 against the end of the tube on opposite sides of the slot, means passing through the end of the end-cap and coacting with the said plate for moving the plate bodily toward the end of the end-cap and a fuse within the 20 tube electrically connected to the end-cap.

In testimony whereof I affix my signature.

ARCHIE W. STEELE.
